APPARATUS FOR CLEANING TEXTILE FIBERS

Manfred T. Hoffman, Newburyport, Mass.

Application May 11, 1944, Serial No. 535,086

4 Claims. (Cl. 19—98)

1

The general object of the invention is to provide an improved process and apparatus for the removal of foreign matter and impurities from textile fibers in general, and in particular to remove such matter and impurities from wool and other textile fibers of animal origin, mechanically to a degree of completeness such as will eliminate or reduce the need for the acid carbonizing of wool fibers in order to remove the burrs, seeds, straw, shives, and other foreign impurities picked up by the wool during its growth, and also the need for the depitching process employed to remove paint and tar commonly present on the fibers. The treatment of the wool fibers with acid, either as loose stock or as cloth, followed by heating the wool to char the impurities, and the usually necessary subsequent neutralizing of this acid with alkali, tend to reduce the felting power of the wool fibers and to injure its other desired qualities, and hence a commercially practicable method of attaining equivalent results in the way of removing foreign impurities without resort to such chemical treatments has long been desired, but never previously attained, as far as I am aware. The depitching process is commonly a separate step, involving a further operation employing solvents and additional machinery, adding to the expense of preparing the wool.

No commercially successful method of attaining the complete removal of these foreign impurities without resort to the use of acid and other chemical solutions has hitherto as yet been devised, so far as known to me. To be sure, a large part of the foreign matter is removed from the loose stock in the dusting or opening machines, in the scouring and rinsing, or equivalent washing and depitching process, in the burr-picker, and in the carding machines, and in the incidental dusters and ceiling condensers widely employed at intermediate steps in the progress of the loose stock through these various machines. But in spite of all such treatment, bits of foreign matter still remain clinging to the fibers requiring for most purposes the previous acid carbonizing and subsequent crushing and dusting for their complete removal.

The crushing of the foreign impurities in the wool fibers without carbonizing with acid has been resorted to in the effort to reduce to dust as much as possible of the quantity of the burrs, seeds, nips, shives, paint, tar, and other foreign bodies so that this pulverized part would be removed in the course of the travel of the stock through certain of the machines named. This

2

method has been practiced by subjecting the wool to heavy pressure between smooth-surfaced rolls when the wool is spread out in a very thin sheet on the order of from one fiber to a half-dozen fibers thick, and for this purpose the wool has been fed to the crushing rolls in the form of the full width web which is stripped from the doffer of a card by the doffer comb. An example of crushing rolls adapted for this purpose is shown in the U. S. Patent No. 2,075,156, granted on March 30, 1937, to Antonio Peralta Albero, which device is known as the Peralta machine, and is located between the first and second cards, or between the second and third cards, of a set of woolen cards, the two cooperating rolls receiving the flat web from the doffer of one card and feeding it, usually by intermediate feeding devices, to the next succeeding card in the set.

Thus employed, the set of cards with the aid of the Peralta machine regularly eliminates from 20 60% to 70% and in special cases as high as 80%, of the foreign matter present in the stock as it arrives at the set of cards. Naturally, efforts have been made to improve the cleaning effected 25 in this way, on the principle that if one crushing eliminates so much of the foreign matter, a second crushing might eliminate all the rest. However, it has been repeatedly found that the use of a second Peralta machine following the first 30 Peralta machine in the same set of cards to perform a second crushing action on the carded web only increases the cleaning about 3% or 4%, which because of the high cost of these Peralta machines is an economically inadequate degree 35 of improvement prohibiting the use of the second of these machines needed to make the process continuous as required in a commercial setup.

I have discovered, however, that if the carded 40 and crushed web issuing from the rolls of a Peralta or similar high-pressure crushing machine is then treated so as to agitate, disturb or rearrange the relationship or lie of the fibers of the stock to each other, preferably with accompanying removal of the part of the foreign matter which has been reduced to dust, and is thereupon subjected to a further crushing, when spread out in a thin web, in another Peralta or equivalent machine, practically the entire remaining part of the foreign matter is pulverized, apparently because of the change in the lie or position of its presentation to the crushing surfaces, so that through subsequent carding or dusting or other cleaning processes substantially 45 55 100% removal of all foreign matter is accom-

plished, with the result that the wool is rendered clean enough for all ordinary purposes to eliminate the need for acid carbonizing of either the stock or the fabric made therefrom.

In accordance with my discovery, and in the effort to simplify and reduce the cost of practicing the process and to adapt the process based on my discovery to exceptionally dirty wools or those containing foreign matter unusually difficult to remove, I have also devised special new machines and combinations of machines for practicing the improved process.

Illustrative embodiments of the application of the process and of the novel machines are shown in the accompanying drawings, in which

Fig. 1 is a diagrammatic side elevation of an arrangement showing the use of existing machines for practicing the invention process.

Fig. 2 is a diagrammatic side elevation of a more elaborate arrangement of existing machines adapted to practice the process of the invention, for use on wool that is more difficult to clean.

Fig. 3 is a diagrammatic side elevation of one card of a set of carding machines, combined with an improved crushing machine of my invention having provision for agitating the fibers of the stock between successive crushings.

Fig. 4 is a diagrammatic side elevation of the improved crushing machine of Fig. 3.

Fig. 5 is a plan view of certain parts of the machine of Fig. 7.

Fig. 6 is a vertical section of the parts shown in Fig. 5, taken on line 6-6 of Fig. 5.

Fig. 7 is a diagrammatic side elevation of one card of a set of carding machines, combined with an improved crushing machine of my invention and also with a series of multiple crush rolls.

Fig. 8 is a diagrammatic side elevation of the improved crushing machine and crush rolls of Fig. 7.

Fig. 9 is a diagrammatic side elevation illustrating an arrangement whereby the output of a plurality of cards is crushed in a single crushing machine of my invention.

Fig. 10 is a schematic plan view of an alternative arrangement for practising the invention.

The practice of the invention process in a simple form with prior existing machines is illustrated in Fig. 1, in which a card 1 of a set of cards forming a carding unit, preferably the first card thereof, feeds its web 2 in flat and full-width relation from the doffer 3 of such card by the medium of apron 7, into the bite between a pair of crushing surfaces comprising the top roll 4 and bottom roll 5 of a Peralta machine 6 according to Patent No. 2,075,156, where the thin web of fibers is subjected to the extremely heavy pressure of the large solid top roll, assisted when necessary by the pressure of the usual springs (not shown) engaging the journals of the top roll and provided to augment the pressure of the top roll when desired. The smooth surfaces of rolls 4 and 5, precision-ground to true cylinder form, crush the major portion of the dirt and foreign vegetable matter into dust, while paint and tar present in the stock adhere to the surfaces of the rolls and are removed therefrom along with such other dirt as may adhere, by scraper blades 8. The crushed web is then transported by apron 9, to a duster, willow, mixing picker or analogous machine 10 of conventional or any preferred design, where the web is completely torn apart by toothed lags, high-speed

fan blades, or other beaters, and the foreign matter previously pulverized by the crushing action of the Peralta machine largely removed by air-currents and centrifugal force through the screens and grids of the duster or similar machine. In certain instances, a hopper feeder having a doffer rotating at fairly high speed and knocking back the stock from the spikes of the lifter apron may be used.

The stock discharged from the duster 10 is then fed as by delivery apron 11 under a hood 12 to the feed rolls of a second card 13, where it is again carded and the web 14 stripped from the doffer 15 is fed by apron 16 between the two rolls 17, 18, of a second Peralta or similar machine 19, identical with the first. In this second crushing effected by the second Peralta or similar machine, the remaining bits of foreign matter are pulverized to a degree of completeness insuring their practical elimination from the stock in its passage through the finisher card or other cards of the set, in the case of wool of average foreign matter content, or for use for most purposes. The crushed web is transported to the next card, or to a duster similar to that indicated at 10 intervening before the next card, by a screen apron 20. In cleaning certain kinds of stock, ceiling condensers may be substituted for the duster, their dusting action being adequate.

Where more complete cleaning is required, or where the nature of the foreign matter makes it more difficult to remove, an alternative setup using prior existing machines is employed as shown in Fig. 2, where the stock is put through the first or other card 21 of a set, thence through a Peralta or similar machine 22, thence either as a web or as loose stock through an extended series of crush rolls 23 of known design similar to that indicated at 74 in Fig. 7, and conventionally used for crushing carbonized stock, through a duster 24, through another series of crush rolls 25, a second duster 26, and thence into a card 27, the web issuing from which is put through a second Peralta machine 28, after which it may be conducted to a finisher card, and/or packed up for sale as cleaned wool. By dint of the added working of the stock by the fluted rolls of the intervening crush rolls 23, 25, and the dusting between and following the operations of these crush rolls, a greater degree of cleaning is effected before reaching the second Peralta machine. With this setup the need for subsequent carbonizing of the wool is entirely eliminated in all but the most exceptional cases. In this, as well as in the arrangement of Fig. 1, the second card shown is employed mainly to perform the function of rearranging the stock in a thin sheet so that the included foreign matter is exposed to the full crushing action of the second Peralta machine.

This sequence of machines is adapted to be used in a special precleaning unit such as shown in plan in Fig. 10, whereby all or a large part of the stock to be used by a mill is cleaned according to the invention principles at a high rate of production at one locality in the mill, thus lightening the burden of cleaning devolving on the finisher cards and hence enabling the output of each unit thereof to be increased. In this precleaning unit, each of a plurality of carding machines 96 feeds its doffer web into a separate Peralta or equivalent crushing machine 97, from all of which latter machines the stock is conducted by suction pipes or otherwise to a single ceiling condenser 98 which removes a part of the

dust and deposits the stock on the apron 99 of one or more series of crush rolls 100 similar to that shown at 23 and 25 in Fig. 2 and at 14 in Fig. 7. The stock emerging from the crush rolls 100 is then fed into one or more dusters or equivalent machines 101 where the pulverized foreign matter is removed, and the stock emerging from the duster is conducted to a bin 102, whence it is distributed by gravity chutes or otherwise to the feed aprons of a plurality of carding machines 103 whence the doffer webs are crushed in individual Peralta or equivalent machines 104 and the crushed stock is collected by a common ceiling condenser or other cleaning device 105 and delivered to the bagging pit for bagging, or to any other point desired, for further processing.

As the use of a plurality of Peralta machines in accordance with the invention increases the cost of the machines needed to practice my improved process, and also because their extreme weight limits their location in the mill or requires special support of the floors, I have devised improved mechanism for performing the same crushing function as the Peralta machine, which new mechanism performs in one unit a plural or repeated crushing action; and I have replaced the dead weight of the solid rolls by hollow rolls, providing hydraulic, pneumatic, or other powerful means for pressing the rolls together to attain the requisite intense pressure at the nip of the rolls to crush the foreign matter. Thus, as shown in Fig. 3, the new crushing machine 29 which operates on the web delivered to it by apron 30 from doffer 31 of the first or other card 32 of a set, comprises a single roll 33, Figs. 3 and 4, equipped with a scraper 34 and wiper roll 35, which rests upon two other rolls 36, 37, arranged in horizontally spaced relation in suitably fixed bearings. Thus the web is first crushed between large roll 33 and small roll 36, and then again crushed between roll 33 and small roll 37, and preferably is agitated at intermediate points between these two crushing operations by a blast of compressed air issuing from a series of nozzles 38 extending across the width of the web and directed obliquely against the under side of roll 33, aided, when deemed desirable, by mechanical agitation by means in the form of a brush, herein a wire-clothed roll 39 having long, resilient wire teeth, like a fancy roll on a card, the tips of the wires having the same direction and having a different speed than the traveling web, herein traveling at slightly increased speed, so that the blast of air, or the combined pneumatic and mechanical action of these agencies disturbs and shifts the order or relationship of the fibers of the web and presumably the position or lie of the particles of foreign matter therein, between the two crushings. Super-sonic devices or static electricity may be used in place of or in addition to the elements 38, 39, to effect the agitation of the stock at this point. Thus the bits of foreign matter left incompletely crushed on passing roll 36 are reduced to dust in the second crushing between roll 37 and large roll 33. On issuing from the nip of rolls 33 and 37, the web is sucked into the intake flue 40 of a duster 41, corresponding to the duster 10 of Fig. 1, from which the stock is fed onward to the succeeding cards in a set of cards as for example in Fig. 1, emerging from the finisher card thereof in substantially completely cleaned condition. As shown in Fig. 4 top roll 33 is hollow, and has its journals

mounted in bearings 42 which have capacity for slight vertical movement in suitable ways 44 in the frame of the machine, each bearing being connected with a piston 45 working in a cylinder 46 to which compressed air, water, oil, or other fluid is fed under pressure via pipe 47 to force piston 45 powerfully downward and thus to develop the requisite pressure between top roll 33 and lower rolls 36, 37. The three rolls are driven by any suitable or preferred known means, and may be driven in analogous manner to that shown in Figs. 5 and 6.

An alternative form of the plural-crushing machine illustrated at 29 in Fig. 3 is shown in Figs. 5 and 6 in which the agitation or shifting of the fibers in the course of the crushing operation is attained in different manner. In this embodiment, the large top roll 48 works against two horizontally spaced smaller bottom rolls 49, 50, which rotate at slightly different, herein slower, peripheral speed than does the surface of top roll 48, thereby creating a slight rubbing or grinding action between the rolls which more effectively breaks up and pulverizes the foreign matter therein. This unequal speed drive is effected by gear 51 on a drive shaft 52 connected with a suitable source of power (not shown) and engaging with gear 53 fixed on the end of shaft 54 of roll 50, which gear 53 also engages with a wide-faced large gear 55 fixed on shaft 56 of top roll 48. A gear 57 fixed on shaft 58 of roll 49, and either identical with or slightly larger or smaller than gear 53, also engages with top roll gear 55 to drive roll 49, like roll 50, at a different surface speed from top roll 48.

To increase further the rubbing action on the stock and its foreign matter, if desired, top roll 48 is reciprocated axially with respect to the bottom rolls, by an eccentric 59 fixed on a shaft 60 which is rotated by bevel gears 61, 62, driven by the extended end of shaft 58 of bottom roll 49. This eccentric is surrounded by a strap 63 attached by pivot pin 64 to a collar 65 surrounding the end of shaft 56 on top roll 48, and rotatably connected with the end of shaft 56 by means of a screw 66 having its end located in a groove in the end of such shaft. Thus, as the rolls rotate, top roll 48 is reciprocated axially with respect to bottom rolls 49, 50.

To increase the grinding action thus attained on the foreign matter when necessary in certain instances, the surfaces of one or more, or all, of the three rolls are slightly roughened, as by sand blasting or cutting very fine flutes or grooves therein, or by knurling the surfaces. In these ways, a more complete pulverizing of certain forms of foreign materials and an accompanying freeing and pushing out of the clinging particles, can be attained with a reduced pressure of the rolls against each other thus preventing harm to certain classes of wool fibers. In other instances, the agitating air blasts produced by nozzles 38 of Fig. 4, and the mechanical disturbances of the relation of the fibers by stirrer roll 39 of such figure, working between the two lower rolls against the under side of top roll 48 and the web traveling thereon, are also employed in this machine. As in the case of the embodiment of Figs. 3 and 4, hydraulic cylinders having their pistons connected to the journals of the top roll, preferably a hollow roll as in Fig. 4, are employed to create the desired crushing pressure between the top roll and the two bottom rolls.

Heating the crushing rolls has been found ad-

vantageous in removing foreign matter, particularly in causing some types of the paint and tar present as impurities in the wool to adhere to the surfaces of the rolls and thus to be extracted from the fibers. For this purpose, any suitable or preferred means of heating the rolls is employed, in the present instance comprising infra-red electric light bulbs 70 in reflecting troughs 71 extending across the full width of the rolls and directing radiant heat against the surfaces thereof to keep the rolls moderately hot.

This machine of Figs. 5 and 6 is ordinarily made of a width to take the full-width web from the doffer of the first or other card of a set of carding machines. An example of an advantageous arrangement for using this machine is shown in Fig. 7, in which the web from the doffer 72 of a card 73 is crushed between the rolls 48, 49, and 50 of the machine of Figs. 5 and 6, and then fed through a set of conventional crush rolls 74, after which it is put through one or more dusters (not shown) after the manner of Fig. 2 and then carded in the remaining cards of the set without need for further crushing or for subsequent acid carbonizing. The invention principle of agitating the fibers between or during successive crushings can also be applied to the crush rolls 74 if desired, as shown in Fig. 8, in which the web crushed between rolls 48, 49, and 50 or the loose stock, if a suction fan, duster, or the like is interposed, passes between a staggered series of rolls, preferably fluted as usual, of which the bottom rolls 75 rotate in fixed bearings and the upper rolls 76 are pressed forcibly downward either by the use of springs 77 and screw means 78 or by pistons 79 working in hydraulic cylinders 80, the fibers and foreign matter being agitated by compressed air jets issuing from nozzles 81 directed against the web where supported by the under sides of top rolls 76, or by relative axial movement of the rolls as in Figs. 5 and 6. Thereafter, the fibers are freed from the pulverized foreign matter in one or more dusters, or in a ceiling condenser, or even merely in the course of their passage through the succeeding card or cards of the set, depending on the amount of impurities present, the crushing in this instance having been carried to an extremely complete extent.

The machine of Figs. 5 and 6 can be made of greater width so as to receive and crush, simultaneously and side by side, the webs from two or more cards of standard width. Thus, the crushing rolls 48, 49, 50, of 120 inches in length, will receive the webs from two 60-inch card cylinders, these cards and the new machine forming a special pre-carding unit, each card having a cylinder of larger diameter and more workers and strippers than normal, permitting it to be speeded up to give a far larger production than usual while still forming a web suitable for the action of the crushing rolls. The latter run at equivalent speed, so that this pre-carding unit will give sufficient production to supply three or four standard sets of cards with cleaned stock, in cheaper and more efficient manner than by supplying each set of cards with its own crushing machine or machines, and under favorable conditions enabling reduction in the number of cards needed in a set, as from four to three or less carding machines. Alternatively, a single special card of 120" or so width can be used for the same purpose.

A related arrangement providing for doing the crushing of the carded web from a plurality of

cards in a single machine and operation is shown in Fig. 9, in which the web 82 from one card 83 is fed between the bottom roll 84 and the next higher roll 85 of a vertical stack of crushing rolls 86, while the web 87 from a second card 88 at the other side of the stack is fed in the opposite direction between roll 85 and the next succeeding upper roll 89 of the stack. The web 90 from still another card (not shown) located behind card 10 83 is brought over such card in flat relation by conveyor aprons 91, 92, and fed between top roll 93 of the stack and the roll immediately below it. Additional webs from still other cards can be brought to the stack in analogous manner by the addition of still further rolls to the stack. Upon emerging from the bite of the rolls, the fibers of each web are sucked into the intake slots of full width nozzles 94 of a suction conveyor conduit 95 transporting the fibers with their pulverized foreign matter to a duster or equivalent machine for separation of the dust from the stock, the latter being thereafter processed in any of the ways indicated hereinbefore, serving to supply clean stock to a plurality of sets of cards.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but

35. What I do claim is:

1. Crush rolls for pulverizing foreign matter present in wool and other textile fibers, comprising in combination opposed rolls repeatedly pressing the fibers between them with pressure sufficient to pulverize a substantial portion of the foreign matter present in the fibers, and means producing air-blasts disturbing the lie of the fibers with respect to each other between successive pressings by the rolls.

45. 2. Crush rolls for pulverizing foreign matter present in wool and other textile fibers, comprising in combination opposed rolls crushing the foreign matter as the fibers pass between them, means rotating the rolls at unequal surface speeds, means imparting axial movement to at least one of the rolls, and means heating at least one of the rolls.

55. 3. In apparatus for removing foreign matter from wool and other textile fibers, in combination, a plurality of carding machines, means subjecting the web issuing from each carding machine to pressure sufficient to pulverize a part of the foreign matter present in the fibers, a crush roll unit, means combining and delivering the thus pressed webs from all the carding machines to the crush roll unit, means pneumatically removing pulverized matter from the fibers after passing through the crush roll unit, a plurality of additional carding machines, and means feeding the fibers thereafter to the latter carding machines.

70. 4. In apparatus for removing foreign matter from wool and other textile fibers, in combination, two rolls in spaced and parallel relation, a third roll bearing against both of the other two rolls, means feeding a web of fibers between the third roll and the other two rolls, means directing blasts of air against the web in the span thereof between the two rolls arranged in

9

spaced and parallel relation, and mechanical means agitating the fibers of the web in the same span.
